UNITED STATES PATENT OFFICE.

WILLIS F. WALKER, OF SIESHOLTZVILLE, PENNSYLVANIA.

RAIL JOINT.

Application filed May 16, 1925. Serial No. 30,797.

To all whom it may concern:

Be it known that I, WILLIS F. WALKER, a citizen of the United States, residing at Siesholtzville, in the county of Berks and State of Pennsylvania, have invented a new and useful Rail Joint, of which the following is a specification.

This invention aims to provide a novel means whereby the ends of a pair of rail-
10 road rails, at a joint, may be held securely against being forced downwardly by the wheels of rolling stock. Generally stated, the object of the invention is to bridge railroad joints in such a manner that the rail
15 treads will be on the same plane and the rail be caused to distribute the wheel loads uniformly to all the cross ties.

It is within the province of the disclosure to improve generally and to enhance the
20 utility of devices of that type to which the invention appertains.

A preferred form has been shown, but it is to be understood that a mechanic working within the scope of what is claimed, may
25 make such changes as his skill may suggest, without departing from the spirit of the invention.

In the drawings:—Figure 1 shows in top plan, a device constructed in accordance with
30 the invention, parts being in section; Figure 2 is a side elevation; Figure 3 is a cross section on the line 3—3 of Figure 2.

The numeral 1 marks the meeting ends of a pair of rail-road rails, each rail comprising a ball 2, a web 3 and a flange 4. Bridge bars 5 are provided and are equipped upon their upper and lower edges with oppositely slanting surfaces 6 which are disposed symmetrically with respect to a median longitudinal plane A—B. Figure 3 shows that the bridge bars 5 are located on opposite sides of the webs 3 of the rail ends 1, the inner slanting surfaces 6 of the bridge bars cooperating respectively, with the under surface of the ball 2 and with the upper surface of the flange 4. Adjacent to their ends, the bridge bars 5 are supplied with pairs of openings 7. Near to one end, each bridge bar 5 has outer tapered recesses 8, and near
45 to its opposite end, each bridge bar has inner tapered recesses 9, the recesses communicating with the openings 7. Owing to the fact that the recesses 8 and 9, located as described, are provided, and because the slanting surfaces 6 of the bridge bars are disposed symmetrically with respect to the

plane A—B, each bridge bar is capable of end for end reversal and axial reversal.

The device comprises U-shaped fastening devices 10, such as U-bolts, each including an intermediate portion, and arms. The arms of the respective fastening devices may be extended in opposite directions through the webs 3 of the rails, and through the openings 7 of the bridge bars, as Figure 1 shows. Between each bridge bar 5 and the intermediate portion of the corresponding fastening device 10 there is placed a saddle 11, the saddle being in the form of a detachable block, fitting closely within the bend of the fastening device, and provided upon its outer end and on its side with a seat 12, which, receiving the intermediate portion or bend of the fastening device, aids in holding the saddle in place. The upper and lower surfaces of the saddle 11 diverge, as indicated at 14. This gives the saddle 11 a broad and firm bearing base to engage the outer surface of the bridge bar 5.

Nuts 15 or other securing elements are mounted on the arms of the fastening devices 10 and have tapered ends 16 which are received rotatably in the outer recesses 8 of the bridge bars 5. This detail, especially in combination with the saddles 11, gives the fastening devices a secure hold on the bridge bars 5 and causes the inner slanting surfaces 6 of the bridge bars to cooperate properly with the ball 2 and the flange 4 of each rail end. It is to be observed that the bridge bars 5 have no lateral flanges at their lower edges. Such lateral flanges, although promoting lateral stability where lateral stability is not necessary, tend to cause a spreading of the rail joint under superposed load.

The device forming the subject matter of this application bridges rail-road rail joints in such a manner that the rail treads will remain on the same plane, and the rails distribute the wheel loads uniformly to all of the cross ties, low joints being done away with.

Having thus described the invention, what is claimed is:—

1. In a device of the class described, rails each including a ball, a web, and a flange, the lower surface of the ball and the upper surface of the flange converging inwardly, bridge bars having inwardly converging edges cooperating with said surfaces of the ball and of the flange, the bridge bars be-

ing spaced from the web, fastening devices including arms and an intermediate portion, the arms passing through the bridge bars and the webs, saddles within the securing devices and engaging one bridge bar, the saddles completely filling the space defined by said bridge bar and the arms and the intermediate portion of the fastening devices, means for holding the saddles against movement within the fastening devices, and nuts on the arms and engaging the other bridge bar, the nuts having rounded ends, and said other bridge bar having concaved recesses receiving the rounded ends of the nuts.

2. In a rail joint, bridge bars; a fastening device comprising arms and an intermediate portion joining the arms, the arms extending through the bridge bars, a saddle located between one bridge bar and the intermediate portion of the fastening device, the saddle having a seat wherein the intermediate portion of the fastening device is received; and securing elements on the arms of the fastening device, the securing elements comprising tapered parts, and the other bridge bar having tapered recesses wherein the tapered parts of the securing elements are received.

3. In a rail joint, bridge bars; fastening devices each comprising arms and an intermediate portion joining the arms, the arms of the respective fastening devices extending in opposite directions through the bridge bars; and a saddle located between each bridge bar and the intermediate portion of one fastening device, each saddle having a seat wherein the intermediate portion of the corresponding fastening device is received.

4. In a rail joint, bridge bars; fastening devices each comprising arms and an intermediate portion joining the arms, the arms of the respective fastening devices extending in opposite directions through the bridge bars; a saddle located between each bridge bar and the intermediate portion of

one fastening device; and securing elements on the arms of the fastening devices, the securing elements comprising tapered parts, the bridge bars having tapered recesses wherein the tapered parts of the securing elements are received.

5. In a rail joint, bridge bars; fastening devices each comprising arms and an intermediate portion joining the arms, the arms of the respective fastening devices extending in opposite directions through the bridge bars; a saddle located between each bridge bar and the intermediate portion of one fastening device, each saddle having a seat wherein the intermediate portion of the corresponding fastening device is received; and securing elements on the arms of the fastening devices, the securing elements comprising tapered parts, the bridge bars having tapered recesses wherein the tapered parts of the securing elements are received.

6. In a rail joint, bridge bars; fastening devices each comprising arms and an intermediate portion joining the arms, the arms of the respective fastening devices extending in opposite directions through the bridge bars; a saddle located between each bridge bar and the intermediate portion of one fastening device; and securing elements on the arms of the fastening devices, each bridge bar being provided on its inner surface with recesses, and being provided upon its outer surface with recesses, the securing elements having parts received rotatably in the outer recesses, each bridge bar being supplied on its upper and lower edges with oppositely slanting surfaces which are disposed symmetrically with respect to a longitudinal plane, the symmetrical disposition of said surfaces, and the provision of the inner recesses, permitting both an axial and an end-for-end reversal of each bridge bar.

In testimony that I claim the foregoing as my own, I have hereto affixed my signature.

WILLIS F. WALKER.
